US00D934359S

(12) **United States Design Patent** (10) **Patent No.:** **US D934,359 S**
(45) **Date of Patent:** **** Oct. 26, 2021**

(54) **PORTABLE GOAL**

(71) Applicant: **Jamberly Group, Inc.**, Louisville, KY (US)

(72) Inventors: **Kim Strong**, Louisville, KY (US); **Jamye Baker**, Largo, FL (US)

(73) Assignee: **Jamberly Group, Inc.**, Louisville, KY (US)

(**) Term: **15 Years**

(21) Appl. No.: **29/664,299**

(22) Filed: **Sep. 24, 2018**

(51) **LOC (13) Cl.** **21-02**

(52) **U.S. Cl.**

USPC **D21/702**; D23/303; D23/305

(57) **CLAIM**

The ornamental design for a portable goal, as shown and described.

DESCRIPTION

FIG. 1 is a perspective view of a portable goal showing our design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

(Continued)

The broken lines depict portions of the portable goal that form no part of the claimed design.
